PROTECTIVE GUARD FOR CUTLERY

Udo Bosnyak, Mariazellerstr. 70,
8605 Kapfenberg, Austria

Filed Mar. 10, 1972, Ser. No. 233,853

Term of patent 14 years

Int. Cl. D7—99

U.S. Cl. D7—74

FIG. 1

FIG. 3

FIG. 1 is a side elevational view of a protective guard for cutlery showing my new design;

FIG. 2 is a top plan view thereof; and

FIG. 3 is a top perspective view thereof.

The side not shown and the bottom are, respectively, a mirror image of the side shown and substantially plain and unornamented.

I claim:

The ornamental design for a protective guard for cutlery, as shown and described.
